CLAIM

I claim the ornamental design for a TAILGATING SHED, as shown and described.

DESCRIPTION

The broken lines depict portions of the tailgating shed that form no part of the claimed design.

FIG. 1 is an elevational view of the front of a tailgating shed.

FIG. 2 is a perspective view of the right side and back of a tailgating shed.

FIG. 3 is an elevational view of the left side of a tailgating shed.

FIG. 4 is an elevational view of the back of a tailgating shed.

FIG. 5 is a perspective view of the top and front of a tailgating shed.

FIG. 6 is a perspective view of the bottom and front of a tailgating shed.
